DRY SHAVING DEVICE

Irving S. Bodkin, New York, and Conrad R. Schumacher, Lynbrook, N. Y.

Application July 21, 1937, Serial No. 154,702

17 Claims. (Cl. 30—43)

The present invention relates to shaving devices and more particularly to shaving devices having shearing elements adapted to cut hair without the aid of lather, cream or other shaving preparations.

One of the difficulties with shaving devices of the above type is that they do not cut or shear hairs as closely to the skin as safety razor blades or hollow ground razors, chiefly because the hairs usually must project through slots or recesses of a guard plate mounted over the shearing elements which sever the hairs. In spite of the thinness of the guard plate or "blades" provided by the slots, the hairs are not clipped closely and a comparatively high degree of skill is required to manipulate the devices in order to attain good results. Invariably, a number of hairs enter the slots improperly, or not at all, and are not cut by the cutting member. As a result, the shaving operation must be repeated several times before a clean shave is attained or shaving at more frequent intervals is necessary. This is objectionable because the time required to shave each day is materially increased.

Another objection to shaving devices of the above type which are now known, is that the guard plate is usually extremely thin and is easily bent or otherwise damaged. Much difficulty is encountered in cleaning the device because the guard plates must be handled very carefully to prevent accidental bending thereof or dulling the "blades." Also, the cutting parts are not readily taken apart and put together again after cleaning, whereby upon operation, they fail to cooperate properly to cut the hair. In many cases, effective cleaning of the cutting elements is not feasible because they are not readily accessible.

The present invention aims to overcome these difficulties by providing an improved dry shaving device adapted to give a close shave which compares with shaves attainable by using a razor, but without cutting, scraping, or irritating the skin. A further aim is to provide a simple, inexpensive shaving device constructed of rugged parts which are adapted to withstand rough usage, which can be easily taken apart to permit cleaning, and which can be quickly reassembled.

An object of the present invention is to provide a dry shaving device adapted to give a better shave in a minimum period of time.

Another object of the invention is to provide a shaving device having cutting edges guarded by teeth adapted to receive hairs at the top or sides thereof.

Another object of the invention is to provide a shaving device having a cutting head which need not be held flatly against the face and is easily manipulated without much practice on the part of the user.

Another object of the invention is to provide a shaving device having cooperating parts adapted to present the hairs in such a manner that they can be cut close to the skin without irritating the skin.

Another object of the invention is to provide a shaving device having cutting members cooperating to cut the hair at an angle with respect to the surface of the skin from which the hair is removed.

Another object of the invention is to provide a shaving device having cutting elements which are held resiliently in assembled position and cannot shift out of cooperating alignment during use of the device.

Another object of the invention is to provide a shaving device having cutting members which are readily taken apart to facilitate access for cleaning and can be properly replaced without a great degree of skill or ingenuity on the part of the user.

Another object of the invention is to provide a shaving device constructed of rugged, durable parts which can be frequently cleaned without damage thereof or dulling of the cutting elements.

A further object of the invention is to provide a shaving device having cutting teeth at both sides thereof with the teeth of one side out of alignment with the teeth of the other side whereby the device can cut a dense growth of hair more effectively.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a fragmentary side elevational view, partly in section, of a shaving device illustrating a preferred embodiment of the invention;

Fig. 2 is an exploded perspective view illustrating the cutting elements of the device taken apart for cleaning;

Fig. 3 is a sectional view taken on the line 3—3 of Fig. 1;

Fig. 4 is a sectional view taken on the line 4—4 of Fig. 1 with the guard frame shown in its upper position and in dot-dash lines in its lower position;

Fig. 5 is a fragmentary perspective view illustrating a modified embodiment of the invention;

Fig. 6 is a fragmentary top plan view illustrating another modification of the invention; and

Fig. 7 is an enlarged fragmentary sectional view illustrating the cutting elements at one side of the razor in operation.

Generally described, the preferred embodiment of the present invention comprises a handle or casing for a motor or vibrator, a stationary cutter secured to the end of the handle, a slidable cutter mounted on the stationary cutter adapted to be reciprocated, and a resiliently mounted guard or frame for holding the slidable cutter against the stationary cutter. These parts will now be described in detail in the above mentioned order.

Referring to the drawings and more particularly to Figs. 1 to 4 there is shown a handle 1 providing a casing or compartment for a mechanism adapted to operate the shaving device about to be described. Preferably, the operating mechanism is a small electric motor or vibrator (not shown) as customarily used for shaving devices of the present type, but if desired, the shaving device may be operated by manual means or a flexible shaft rotated by a motor at some remote point. The handle or casing may be constructed of parts formed of any suitable material, for example, Bakelite which is readily molded and assembled, is non-corrosive, affords good insulation, and can be easily cleaned.

The upper end of the handle may be provided with a suitable recess or seat 2 adapted to receive the base or bottom portion 4 of a cutting head or stationary shearing element 5 secured to the handle by screws 6 or other suitable attaching means. Preferably, the cutting head has an upwardly extending flange 7 (Figs. 3 and 4) at each side thereof and a longitudinally extending groove or channel 8 intermediate the flanges. The upper ends of the flanges diverge laterally outwardly and are inclined at an angle of about thirty (30°) degrees to provide upwardly facing portions 9 for mounting a slidable cutting member 10 about to be described. The upper end of each flange has a row of spaced cutting teeth 11 which are provided with laterally inwardly facing cutting edges 12. Preferably, these teeth and the slots or recesses 13 spacing the teeth are relatively narrow to provide a large number of cutting teeth, per unit of length, along the side edges of the stationary cutting member.

The slidable cutting member 10 preferably is substantially V-shaped in section and has divergent flanges 14 adapted to be seated for reciprocating movement on the inclined upwardly facing portions 9 of the flanges. The free ends of the flanges 14 each have a row of spaced cutting teeth 15 provided with laterally outwardly facing cutting edges 16 adapted to cooperate with the cutting edges 12 of the stationary cutting teeth 11. To eliminate any possibility of the cutting edge 16 scraping the skin, they may be positioned slightly below the upper end 16' of the flanges. The upper end 16' is smooth and continuous to prevent any unpleasant sensation if it should engage the skin while the cutter 10 is being reciprocated.

Preferably, the free ends 17 of the teeth 11 extend a short distance, for example about .005 of an inch, above the portion of the cutting teeth at which the shearing action takes place and act as a comb or guard while using the device. These ends 17 may be blunt or rounded so that they will not abrade the skin and are adapted to press the skin downwardly to present the hairs to the cutting edges of the teeth. In this manner, the cutting action may take place very close to the ends 17 of the teeth 11 to provide a close shave and the hairs may extend through the recesses 13 at either the top or sides of the teeth 11 engaging the skin. Also, the cooperating cutting edges 12 and 16 engage along a plane inclined with respect to the base of the stationary cutting head or parallel to the inner faces 9 of the flanges to cut or shear the hairs diagonally or at an angle through the diameter thereof. This eliminates any unpleasant pulling sensation to the skin, similar to that of using a dull razor blade and minimizes the tendency of a coarse beard or thick growth of hair to clog or jam between the cutting edges to further irritate the skin.

The cutting elements 5 and 10 may be readily made of tool steel or any other suitable material adapted to be machined very accurately. If desired, the cutting members may be formed of a stainless steel adapted to resist corrosion or may be subjected to a special hardening process so that the teeth can be provided with very sharp edges adapted to withstand prolonged use without signs of wear or dullness. By making the cutters of a hard metal, they are less expensive, more serviceable and cannot be easily damaged when taken apart for cleaning.

The slidable cutter 10 preferably is reciprocated by a vibrating or oscillating arm 18 pivoted to the casing or handle and operated at its lower end by an electric motor (not shown) or other suitable means. The upper end of the arm extends through a slot or recess 3 in the base 4 of the stationary cutter and fits into a recess 23 or other suitable connecting part at the lower portion of the slidable cutter. If a recess, such as shown, is utilized, the slidable cutter can be readily removed from the vibrating arm 18 for cleaning.

In order to hold the slidable cutting member 10 within the longitudinal groove or channel 8 of the stationary cutting element, a guard member 19 is mounted thereon having a downwardly projecting portion 20 adapted to fit in an upwardly facing groove 21 between the flanges 14 of the slidable cutting member. The guard member 19 preferably engages the inner faces 22 of the flanges 14 at a point below the cutting edges of the teeth and may be provided with bearing portions 24 adjacent the respective ends thereof, and a recess 25 intermediate the bearing portions 24 for spacing the sides of the guard member 19 from the slidable cutting member 10. In this manner, the engaging surfaces of these parts are less likely to wear and the recesses 25 facilitate access for lubrication of the engaging surfaces.

The upper surface 26 of the guard member preferably is smooth and either flat or slightly curved to provide a portion suitable for engaging the surface of the skin, and preferably extends slightly above the teeth of the slidable cutting member 10 to cooperate with the teeth 11 of the stationary cutter and depress or stretch the skin to present the hairs to the cutting edges of the teeth. In practice, it has been found that

good results can be obtained without scraping or injuring the skin if the upper surface 26 of the guard member, at the sides adjacent to the movable cutter, extends upwardly therefrom about .002 to .005 of an inch. This enables a closer shave than can be attained with devices having a thin sheet metal guard plate above the movable cutter. Preferably, the guard member is made of tool steel and can be accurately machined within close limits.

The guard member 19 may be held downwardly against the slidable cutting member in any suitable manner, but preferably is mounted on a frame adapted to be raised to facilitate access to the slidable cutting member 10. Such a frame may comprise a pair of arms or link members 30 each having its upper end pivoted to one end of the guard member in any suitable manner, and a shaft or rod 31 having the other end of each link member attached thereto. Preferably, the link members are arbored to the shaft so that both link members are adapted to rotate simultaneously with the shaft. The shaft extends through a slot or recess 32 in the upper portion of the handle for permitting the frame to be raised upwardly with respect to the cutting head. In order to facilitate manual engagement of the link members, they may be bowed outwardly slightly at 34 and may be provided with a milled or knurled surface 35.

Suitable means for normally holding the shaft downwardly are employed and preferably comprise a pair of slidable pins or plungers 36 mounted in apertures 37 formed in the casing and spring members 39 seated in the apertures above the pins for urging them downwardly against the shaft 31. In order to keep the pins in engagement with the shaft at all times, the lower ends 40 of the pins may be recessed to fit about the top and sides of the shaft (Figs. 3 and 4). Also, it will be noted that spring members 39 are retained against upward movement by the underside of the base of the stationary cutting head which closes the upper ends of the apertures (Figs. 1 and 4). Although other locking means may be utilized for holding the guard frame in its lower position, resilient means are preferred due to the springy engagement of the slidable cutter by the guard. Hence, if any foreign substance should get between the cutting edges and tend to jam the cutting elements, the spring mounting yields slightly allowing the cutting edges to move slightly apart until the foreign substance is discharged.

The frame carrying the guard member is adapted to be raised in opposition to the springs and swing to the front or back side of the handle to permit access to the slidable cutter. In order to guide the links when the frame is raised and oscillated, the ends of the handle have substantially V-shaped recesses 45 (Fig. 2) providing shoulders 46 adapted to act as stops for limiting movement of the links 30. These recesses 45 are readily formed in the handle without increasing the cost thereof. While the frame is raised and swung away from the top of the cutting head, the guard member preferably is held against rotating freely between the upper ends of the links. To accomplish this, the upper ends of the links have inwardly facing projections 49 provided with a substantially flat lower surface 50 (Figs. 3 and 4) for engaging the upper surface 26 of the guard member. Usually, the projections are spaced slightly above the guard member to permit slight tilting movement of the guard mem-

ber for orienting itself while being seated in the groove 21 of the slidable member.

In Fig. 5 there is illustrated a modified frame construction for holding the guard member 19 in operative position wherein the links 30 are pivotally attached to guard member and the shaft or rod 31 for sidewise movement with the reciprocating cutter. To accomplish this the links may be constructed in three parts and may comprise an upper member 51 connected to the guard 19, a lower member 52 connected to the shaft or rod 31, and a link member 30' intermediate the upper and lower members having its respective ends pivotally connected to the members 51 and 52 by suitable pins 53 or the like. Preferably, the link members 30' and the connecting members 51 and 52 have interfitting grooves and projections 54 adapted to prevent longitudinal folding of the link parts 30', 51 and 52 so that the links can be swung forwardly or rearwardly as a unit to the position illustrated in Fig. 5. By making the projections and recesses substantially rectangular, sidewise folding or oscillation of the parts is facilitated and the transversely extending pins cooperate therewith to prevent longitudinal bending thereof. While the links are shown herein hinged at two points, in some instances it may be desirable to provide a single hinge connection, either at the upper or lower end of the link.

The above construction attains several advantageous results. For example, the hinge connections facilitate seating the guard in its proper position on the slidable cutter after the parts have been cleaned. Also, the guard can be reciprocated sidewise by the slidable cutter to reduce friction between the guard and cutter.

While the above frame constructions for removably mounting a guard member are particularly adapted to be used with the improved cutting elements described herein, it will be understood that many features thereof are applicable to other types of cutting elements.

In Fig. 6 a modified stationary cutter is illustrated having a row of cutting teeth 55 spaced by slots 56 at one side and another row of teeth 57 spaced by slots 58 at the other side. The teeth 55 and 57, as indicated by the line M extending transversely across the cutter, are not in alignment but are staggered with respect to each other. In this manner, when the cutter is moved across the surface of the skin, hairs which do not enter the slots 56 enter the slots 58 and are cut. This simplifies and expedites the shaving operation because stray hairs will not be missed and the device need only be applied once to the surface to be shaved.

In enlarged Fig. 7 one side of the shaving device described herein is shown while being used. The top of the shaving head is illustrated applied flatly against the surface of the skin so that the upper side 26 of the guard member and the comb-like ends 17 of the stationary teeth 11 flatten or depress the skin S and present the hairs H to the cutting edges 12 and 16 of the teeth. While only one side of the cutting elements is shown in this figure, the other side will operate in a similar manner to simultaneously cut hairs. By providing two edges, the device, in effect, gives a double shave by only going over the skin once.

Also, good results can be obtained by using only the teeth at one side of the head at a time. For example, the cutter need not be held flatly against the surface of the skin, but may be tilted slightly with respect thereto so that the teeth

at one side are out of engagement. As a result, the handle need not be held perpendicularly with respect to the skin, an awkward position which requires a great deal of practice by the user. The present device can be used more nearly like a safety razor and can be held in a more natural position which is less tiring.

It will be noted that the present device cuts the hairs without the necessity of a slotted guard plate and presents the cutting edges close to the skin somewhat like a blade while the skin is held out of contact with the movable cutter by the outer teeth 11 and the guard member. The degree of closeness of the shave is thus accurately determined and maintained by the dimensions of the guard member and the cooperating cutting teeth. For example, excellent results are attained by providing the cutting edges 12 and 16 of the teeth from .002 to .005 inch from the ends of the teeth 11 and having the surface 26 of the guard member a similar distance above the cutting edges. The ends 16' of the flanges of the movable cutter extend slightly above the teeth and are smooth so that if they do engage the skin, they will have no irritating effect. Any engagement of the skin by the smooth end 16' results in a pleasing, invigorating, massaging sensation. Also, it will be observed that the cutting plane is inclined at an angle with respect to the face and has a razor like action when shearing the hairs.

The present shaving device is primarily designed to shave the beard from the face, but is also adapted to remove superfluous hair from any part of the body. For example, women will find it very useful for shaving under the arms or removing hair from the arms or legs. Since the skin at those places is relatively delicate and tender, the fact that the present device does not irritate the skin is an important feature. The teeth are adapted to shave long or short hairs and a beard which is coarse or fine.

When the shaving device has been used and it is desired to clean the cutting elements and remove hairs which have collected between the parts, the user grasps the knurled portions 35 of the links 30 with the thumb and a finger while holding the handle with the other hand, raises the frame as illustrated in Fig. 4 and swings it across the head, as indicated by the arrows F, to the position shown in Fig. 2. The slidable cutter 10 may then be lifted out of the channel 8 and may be wiped off with a dry rag. The edges of the flanges 7 carrying the stationary teeth are also accessible and may be similarly cleaned. The slidable cutter thereafter is replaced and the guard member is mounted thereon to hold it resiliently against the stationary cutter.

It will be seen that the present invention provides a simple, inexpensive shaving device constructed of a minimum number of parts which are readily assembled and taken apart for cleaning or inspection. A feature of the device is that the cutting action takes place in a plane inclined with respect to the surface of the skin while the teeth of the cutting elements and the surface of the guard member cooperate to present the hairs to the cutting edges and make a close shave possible. Another feature is that cutting teeth are effective to sever hair when either the top or sides thereof engage the faces to provide the sides of the cutting head with a cutting radius of at least ninety degrees. This enables the device to be used for shaving the beard and trimming the sideburns or mustache. A further feature is the

resilient mounting for the slidable cutter and the guard member which is easily removed to clean the cutting elements. Also, the guard when replaced, is guided into proper position to assemble the cutting elements in cooperating relation without skill or ingenuity on the part of the user.

By providing cutting edges at each side of the head, a quicker and cleaner shave is feasible. Also, the cutter head need not be held flat against the face because, if tilted, the teeth on one side are always effective to sever the hairs. The parts of the device are inexpensive to manufacture and rugged in construction and can readily withstand any rough usage to which they may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described our invention, we claim:

1. In a device of the class described, the combination of a member having a longitudinally extending groove in the upper side thereof and upwardly and outwardly inclined cutting teeth adjacent said groove, and a V-shaped member mounted in said groove adapted to be reciprocated with respect to said first member, said second member having upwardly and outwardly inclined cutting teeth the extremities of the V-shaped sides in sliding contact with the teeth of said first member to provide a cutting plane inclined at an angle with respect to the surface 30 of the skin from which hair is to be removed, the ends of the teeth of said first member extending upwardly and outwardly beyond the teeth of said second member, thereby serving as a guard during the cutting operation and the ends 40 of the teeth of said second member being rounded to depress the skin during the cutting operation.

2. In a device of the class described, the combination of a cutting head having an upwardly facing channel and a row of cutting teeth at each side of the channel, a slidable member mounted in said channel having a groove on the upper surface thereof and a row of cutting teeth at each side of the groove with cutting faces thereon facing the cutting teeth of the cutting head and adapted to cooperate with the teeth of said stationary member, and a normally stationary guard member having relatively smooth edges and a portion fitting into the groove for holding said slidable member in the channel, the teeth of said intermediate slidable member being below a plane passing over the surface of the adjacent cutting head and guard member.

3. In a device of the class described, the combination of a cutting head having a row of cutting teeth at one side thereof, a slidable member mounted on said cutting head having a row of cutting teeth adapted to cooperate with the teeth of said cutting head, a guard member above said slidable member, a pivotally mounted link member connected to each end of said guard member, and resilient means for urging said link members downwardly to hold said guard member against said slidable member.

4. In a device of the class described, the combination of a handle having a slot extending therethrough, a cutting head attached to the upper end of said handle, a slidable cutting member mounted on said cutting head, a guard member for holding said slidable member against said cutting head, a link member connected to each

end of said guard member, a shaft member extending through the slot in said handle having each end connected to one of said link members, and means for normally holding said shaft member downwardly in the slot.

5. In a device of the class described, the combination of a handle having a slot extending therethrough, a cutting head attached to the upper end of said handle, a slideable cutting member mounted on said cutting head, a guard member for holding said slideable member against said cutting head, a link member connected to each end of said guard member, a shaft member extending through the slot in said handle having each end connected to one of said link members, and resilient means concealed within said handle for holding said shaft member downwardly in the slot.

6. In a device of the class described, the combination of a handle having a slot extending therethrough, a cutting head attached to the upper end of said handle, a slideable cutting member mounted on said cutting head, a guard member for holding said slideable member against said cutting head, a link member connected to each end of said guard member and extending along the sides of said handle member, said link members having a portion to facilitate manual engagement thereof, a shaft member extending through the slot in said handle having each end connected to one of said link members, and resilient means for holding said shaft members downwardly in the slot.

7. In a device of the class described, the combination of a cutting head having a row of cutting teeth, a slideable cutting member mounted on said cutting head having a row of cutting teeth adapted to cooperate with the teeth of said cutting head, a guard member for slidably mounting said slideable cutting member, link means connected to said guard member, said link means having a hinge between the ends thereof to permit sidewise movement of said guard member, and means connected to said link means adapted to hold said link means and said guard member downwardly.

8. In a device of the class described, the combination of a handle having a slot extending therethrough, a cutting head attached to the upper end of said handle, a slideable cutting member mounted on said cutting head, a guard member for holding said slideable member against said cutting head, a link member connected to each end of said guard member, a shaft member extending through the slot in said handle having each end connected to one of said link members, a plunger member mounted in each of said apertures having a recessed portion adapted to engage said shaft member, and a resilient member in each of said apertures having one end thereof engaging the underside of said cutting head and the other end thereof engaging said plunger member to normally urge said shaft downwardly to hold said guard member against said slideable member.

9. In a device of the class described, the combination of a handle member having substantially a V-shaped shoulder at each side thereof, a cutting head attached to said handle, a guard member adapted to overlie said cutting head, and a link member connected to each end of said guard member, said link members being pivotally mounted on said handle member and adapted to be raised and oscillated with respect to said

handle member to remove said guard member from said head, said V-shaped shoulders of said casing serving as stops for limiting oscillation of said link members.

5 10. In a device of the class described, the combination of a stationary member having a groove therein and a series of laterally extending cutting teeth provided with inwardly facing cutting edges substantially in the form of a V, a V-shaped 10 slideable member mounted in the groove of said stationary member having a series of laterally extending cutting teeth provided with outwardly facing cutting edges adapted to cooperate with the cutting edges of the teeth of said stationary 15 member, the ends of the teeth on the stationary member extending upwardly beyond and outwardly beyond the cutting edges thereof and beyond the teeth of said slideable member to depress the skin and serve as a stationary guard 20 on one side of the cutting zone during the cutting operation, and a stationary holding member extending longitudinally over said slideable member for holding one cutting member against the other with the side edges thereof terminating 25 in adjacent but laterally spaced from the cutting teeth of said slideable member.

11. In a device of the class described, the combination of a cutting head having a longitudinally extending channel in the upper side thereof and 30 a row of cutting teeth at each side of the channel, the teeth at one side of the channel being staggered with respect to the teeth on the other side of the channel, a slideable cutting member mounted in the channel having a groove on the upper surface thereof forming a pair of spaced inclined side portions having teeth adjacent their outer edges adapted to cooperate with the teeth of said cutting head and a guard member having a portion fitting into the groove between 35 40 said spaced inclined side portions for holding said slideable member in the channel.

12. In a device of the class described, the combination of a stationary member having laterally extending cutting teeth provided with lateral 45 cutting edges facing inwardly with respect to the central plane of the stationary member, a slideable member mounted upon said stationary member having laterally extending cutting teeth provided with cutting edges facing outwardly with 50 respect to the central plane of the stationary member and adapted to cooperate with the inwardly facing cutting edges of the teeth of said stationary member, the ends of the stationary teeth extending upwardly beyond and outwardly 55 beyond the ends of the teeth of the slideable member to depress the skin and serve as a guard during cutting operation, and a normally stationary guard member mounted above said slideable member for holding said slideable member 60 against said stationary member and adapted to cooperate with the ends of the stationary teeth to depress and stretch the skin on the respective sides of the cutting teeth of the slideable member and present the surplus hair to be removed to 65 the cutting edges while holding the skin away from the cutting edges.

13. In a device of the class described, the combination of a handle having a pair of divergent inclined flanges at the upper end thereof and a 70 substantially V-shaped channel intermediate said flanges, said flanges having cutting teeth provided with cutting edges facing said channel and a substantially V-shaped member slidably mounted in said channel having cutting teeth 75 provided with rounded ends for depressing the

skin and provided with cutting edges facing the edges of the teeth of said flanges to provide a cutting plane substantially parallel to said flanges and inclined with respect to the upper end of said handle.

14. In a device of the class described, the combination of a stationary member having an upwardly facing longitudinally extending channel substantially V-shaped at its upper portion with a row of cutting teeth at each side of the channel, a V-shaped slidable member mounted in said channel having a groove on the upper surface thereof and a row of upwardly extending cutting teeth at each side of the groove adapted to cooperate with the teeth of said stationary member, means for reciprocating said slidable member, and a guard member having spaced bearing portions at each side thereof for engaging the inclined side walls formed by the groove of said slidable member and a recess intermediate said bearing portions to facilitate lubrication and reciprocation of said slidable member.

15. In a device of the class described, the combination of a handle having a guideway therein and a row of cutting teeth thereon, a movable cutter with a substantially V-shaped bearing surface slidably mounted in the guideway of said handle having a row of cutting teeth thereon adapted to cooperate with the row of teeth on the handle, a guard member normally extending longitudinally above said cutter, and resilient means for normally holding said guard member downwardly and for holding the said movable cutter in operative position.

16. In a device of the class described, the combination of a handle, a stationary member on said handle having an edge portion adapted to

contact the skin and a row of cutting teeth adjacent said edge portion adapted to cut hair close to the skin, a slidable cutting member on said stationary member, a guard member above said 5 slidable member adapted to cooperate with said stationary member to hold the skin out of contact with said slidable member, a frame for mounting said guard member adapted to be raised to permit access to said slidable member, and resilient means for normally holding said frame downwardly.

17. In a device of the class described, the combination of a stationary member having a substantially V-shaped recess therein and a series of laterally extending cutting teeth at each side of said recess provided with laterally inwardly facing inclined cutting edges, a substantially V-shaped slidable member superimposed upon said stationary member and guided by said recess having a series of laterally extending inclined cutting teeth provided with outwardly facing cutting edges adjacent and adapted to cooperate with the cutting edges of the teeth of said stationary member, the extreme outermost portions of the cutting edges of the teeth on said slidable member being exposed and spaced inwardly from the normal plane of contact of said device, normally stationary means separate from the cutting members and free of cutting teeth extending over said slidable member to depress the skin during the cutting operation and for holding said slidable member against said stationary member, and means for reciprocating said slidable member.

IRVING S. BODKIN.
CONRAD R. SCHUMACHER.
